UNITED STATES PATENT OFFICE

EUGENE W. SCHELLENTRAGER, OF SHAKER HEIGHTS, OHIO

COKE-PLANT MACHINERY

Application filed August 26, 1927. Serial No. 215,624.

My invention relates generally to machinery used in coke producing plants and more particularly to machinery used for leveling the coal in the chambers of coke ovens and for pushing the coke out of these chambers.

One of the objects of my invention is to provide a simple and inexpensive and easily and conveniently operable means for leveling coal in the chambers of coke ovens and for pushing coke out of these chambers; to employ one ram to effect the coal leveling as well as the coke pushing; and to provide a coal leveler which properly and efficiently and effectively levels the coal in chambers which are greater in width than in height. Other objects will appear, or become apparent or obvious, or will suggest themselves, during the description of the apparatus shown in the accompanying drawings.

In coke producing plants, coal is first charged into the chambers of coke ovens, usually through one or more charging openings in the tops thereof, and naturally piles up pyramidically or conically in the chambers; such piling up is quite undesirable since the coal should be leveled so that a coal bed of even thickness is provided before the coking process begins and thereby effect proper and even coking as well as proper production of by-products or elimination of by-products material from the coal in addition to many other advantages.

The advantages of such leveling is more pronounced in coking chambers which are greater in width than in height. The problem to be solved then is to devise a leveler head or means which levels the coal properly in such wide ovens or chambers and this problem has been solved in my invention.

In coke plants prior to my invention, a machine, generally known as a coke pusher, was provided with two rams, one below the other and usually to one side of the other for structural and operative reasons, the lower one had a coke pusher head on one end to push the coke out of the oven chambers and the upper one had a leveler head on the same end to level the coal in the chambers. This structure necessitates that the coke pusher machine (a heavy machine) must be moved sidewise

to bring the leveler head into proper position so that the same could enter the door provided on the oven for that purpose and must also be moved sidewise from the positions just described to bring the coke pusher head into proper position so that the same could enter the door provided on the ovens for that purpose. In addition to this double sidewise movement of the heavy pusher machine, it is necessary to operate the rams individually. This sidewise movement of the machine as well as the individual operation of the double ram requires considerable machinery or mechanism and often results in confusion and consequent possible accidents by an operator manipulating the wrong lever or similar mistakes.

All of the above disadvantages are eliminated and other advantages are added in my invention which reduces the cost of construction and of upkeep as well as possible mistakes by operators as well as providing means for leveling coal in wide ovens and pushing coke out of ovens in the most effective and economical manner.

In order to illustrate my invention, I have embodied the same in the accompanying drawings in a certain device or apparatus. I am aware, however, that my invention can be embodied in other devices or apparatuses of a similar nature.

In the accompanying drawings:—

Fig. 1 is a plan view of a portion of a coke plant and shows a portion of a coke oven and a portion of a pusher machine and the ram thereof and a leveler head and a pusher head embodying my invention as related to other elements of the coke oven; a portion of the top of the oven is in section to more clearly show the sidewise relations between the wide oven chamber and the leveler and pusher heads.

Fig. 2 is a side view of Fig. 1 and shows more clearly the vertical relations between elements; the upper portion of the coke oven is shown partly in section to show more clearly how the coal piles up when it is first charged into the chamber; the coke pusher head is shown in full lines as being extended out of

the leveler head and in dot and dash lines as receded into the leveler head.

Fig. 3 is a transverse section of the leveler head, taken in a vertical plane indicated by the line 3—3 in Fig. 2 and shows more clearly the suspension of the pusher head in the leveler head.

Fig. 4 is a longitudinal section of the leveler and pusher heads taken in a plane indicated by the line 4—4 in Fig. 1 and shows more clearly the suspension of the pusher head in the leveler head and the mechanism for operating the pusher head which is here shown in full lines as receded into the leveler head and in dot and dash lines as extended out of the leveler head.

Similar reference characters refer to similar parts throughout the views.

The coke oven A has the coking chamber 10 one end of which is closed by the vertically slidable door 11 which closes the lower portion of the chamber and the hinged and upwardly swivable door 12 which closes the upper portion of the chamber. The door 12 is to be opened when coal is to be leveled in the chamber and the door 11 is to be opened in addition to the opening of the door 12 when coke is to be pushed out of the chamber.

The larry or coal charging car B has the spout 13 which discharges the coal C from the larry into the chamber through the opening 14 which coal, naturally, piles up conically and must be leveled before the coking process begins to produce an even bed of coal for proper coking as well as for proper isolation of by-products. The line 15 indicates the coal level in the present instance.

The pusher machine D has the ram 16 reciprocatably operated by the toothed pinion 17 in mesh with the toothed rack 18. The pinion can be operated by any suitable source of power.

The leveler head E is secured to one end of the ram 16 and is, in the present instance, built up of sheet metal in pyramidal form with the flat walls 19 and 20 at each traverse end and the wall portions 21, 22, 23, 24, 25 and 26; each of these portions being itself inclined and each of these portions being inclined in relation to each other portion. The leveler head can be made conical with a round base or of other formation with the inclined surfaces thereon and angular with each other or with at least some of the surfaces at an angle with each other.

This structure provides a hood like hollow leveler head, closed all around except at the bottom where it is open and the pointed edges 27 and 28 and a plurality of plow-share-like surfaces radiating from these points so that these points and surfaces can and do scatter the conically piled coal and move it sidewise and forwardly and backwardly in the manner of a plow and thereby level the coal when the ram is reciprocated in the chamber 10.

The ears 29 of the pusher head F are pivoted on the shaft 30 journaled in the bearing blocks 31 secured to the inner surface of the walls of the leveler head. The body portion 32 of the pusher head extends the full width of the leveler head and has the stiffening toe 33 and the boss 34 substantially in the middle of the toe.

The shaft 35 is journaled in the bearing blocks 36 secured to the inside of the walls of the leveler head and the bell crank 37 is carried by the shaft 35 between the blocks 36. The links 38 have one end thereof hinged to the end 39 of the bell crank and the other end thereof hinged to the boss 34.

All of the walls of the leveler head are flush on the bottom and substantially in alignment with the line 15; the leveler head is hollow and open at the bottom; the shaft 30 is positioned so that the portion 32 of the pusher head is flush with or inside of the bottom of the leveler head; and the shaft 35 is positioned so that the axis of the crank 39 is in alignment with the axis of the links 38 and so that this aligned axis intersects the axes of the shafts 30 and 35. This arrangement forms an abutment for the pusher head to prevent the same from swiveling backwards when the same is pushing coke out of the chamber.

The bar or cable 40 is secured to the end 41 of the bell crank and serves the purpose of raising the pusher head out of the operating position thereof and receding the same up into the leveler head. Upon release of the cable 40, the pusher head drops down into operating position due to the gravity thereof.

When the ram is moved longitudinally toward and into the chamber 10, the point 27 digs into the coal C as indicated in dotted lines and the surfaces 23 and 24, assisted by the surfaces 21 and 22, move and scatter some of the coal sidewise similar to a plow and also move some of the coal inwardly of the chamber to level the same in all directions.

When the ram is moved longitudinally in the opposite direction in the chamber, the point 28 and the surfaces 25 and 26 act in a similar manner but in an opposite direction and scatter the coal in opposite directions. Repeated reciprocation of the leveler head eventually levels the coal in the chamber properly. During this coal leveling operation, the end 41 of the bell crank 37 is practically horizontal, the links 38 and the portion 32 are moved up into the hollow of the leveler head so that no mechanism projects or extends below the bottom of the leveler head; and the cable 40 retains these elements in position.

After the coking operation or process is completed, or when the coke is to be pushed out of the chamber, the cable 40 is released whereupon the portion 32 swivels on the shaft 30 and drops downwardly until the crank 39

and the links 38 assume the described aligned and abutting relation and the pusher head is then in operative position and is securely abutted to prevent the shifting thereof.

5 When the ram is moved toward one end of the chamber 10, the portion 32 of the pusher head abuts one end of the coke in the chamber and pushes the same out of the other end of the chamber by means of the extended pusher head.

10 The mechanism shown and described levels coal in coke ovens and pushes coke out of the ovens in an effective and economical and efficient and easily operable manner.

15 I am aware that changes can be made in the structure as well as in the arrangement of the elements shown and described as well as in the general application of my invention within the scope of the appended claims; therefore, without limiting myself to the precise structure and arrangement of elements as shown and described nor to the precise general application of my invention as shown and described,

20 I claim:—

1. A coke plant machine including a ram, a leveler head on said ram, and a pusher head having one edge thereof hinged onto said leveler head and a toggle joint means to swivel said pusher head into a receding position in said leveler head and out of said leveler head and into operative position.

2. A coke plant machine having a movable ram including a leveler head, a pusher head on said leveler head and movable into and out of the same, means for moving said pusher head, and means for locking said moving means when said pusher head is moved out of said leveler head.

3. A coke plant machine including a longitudinally movable ram carrying a coal leveler head, a coke pusher head pivoted on said leveler head, and an operating mechanism to move said pusher head into and out of coke pushing position so that coal can be leveled in and coke can be pushed out of an oven while said ram is in one lateral position.

4. A coke plant machine including a longitudinally movable ram, a hollow coal leveler head on said ram, a coke pusher head movably carried by said leveler head, and an operating means to move said pusher head into and out of said leveler head so that coal can be leveled in and coke can be pushed out of an oven while said ram is in one lateral position.

5. A coke plant machine including a longitudinally movable ram, a hollow leveler head on said ram, and a pusher head movably carried by said leveler head and selectively recedable into and extendable out of said leveler head so that coal can be leveled in and coke can be pushed out of an oven while said ram is in one lateral position.

6. A coke plant machine including a longitudinally movable ram, a hollow leveler

head on said ram, a pusher head pivoted onto said leveler head and an operable lever means to pivot said pusher head into and out of said leveler head so that coal can be leveled in and coke can be pushed out of an oven while said ram is in one lateral position.

7. A coke plant machine including a longitudinally movable ram, a leveler head on said ram, and a pusher head hinged onto said leveler head and selectively operable so that coal can be leveled in and coke can be pushed out of an oven while said ram is in one lateral position.

8. A coke plant machine having a movable ram including a pyramidal leveler head, a pusher head movably suspended on said leveler head, and means to move said pusher head so that coal can be leveled in and coke can be pushed out of an oven while said ram is in one lateral position.

9. A coke plant machine having a ram movable into and out of and in a coking oven, a coal leveler head on said ram and having plow-share-like wall portions to level the top of coal in said oven when said ram is moved in said oven, a movable coke pusher head carried by said leveler head, and control means operable to move and confine said pusher head into said leveler head during a coal leveling operation and to move the same out of said leveler head for a coke pushing operation and to retain the same in that position.

10. A coke plant machine having a ram movable into and out of and in a coking oven, a coal leveler head on said ram and having plow-share-like walls to level the top of coal in said oven when said ram is moved in said oven, a movable coke pusher head carried by said leveler head, and means to retain said pusher head within said leveler head while coal is being leveled in said oven and to move said pusher head out of said leveler head when coke is to be pushed out of said oven.

11. A coke plant machine having a reciprocatable ram movable into and out of a coking oven, a hollow pyramidal coal leveler head on said ram to level coal in said oven and having the wall thereof composed of differently inclined portions to level coal in said oven with a minimum of coal resistance against the same, a movable coke pusher head on said leveler head and mounted to be receded into the same while said leveler head is leveling coal in said oven and to be extended out of said leveler head when coke is to be pushed out of said oven, and means to extend and to recede said pusher head.

12. A coke plant machine having a reciprocatable ram movable into and out of a coking oven, a hollow pyramidal coal leveler head on said ram to level coal in said oven and having the wall thereof composed of dif-

ferently inclined portions to level coal in said oven with a minimum of coal resistance against the same, a movable coke pusher head on said leveler head and mounted to be re-
5 ceded into the same while said leveler head is leveling coal in said oven and to be ex-
tended out of said leveler head when coke is to be pushed out of said oven, abutment means to retain said pusher head in coke
10 pushing position, and means to move and re-
tain said pusher head into said leveler head when coal is to be leveled in said oven.

13. A coke plant machine including a ram, a head on said ram and formed to level coal
15 in a coking oven, a coke pusher means move-
able on said head, and an operable means to move said pusher means into a position to push coke out of the oven and into a position which does not interfere with the level-
20 ing of coal in the oven.

14. A coke plant machine having a longitudinally movable ram and a coal leveler head on said ram and terminating in a point at the front bottom end thereof and walls slop-
25 ing upwardly rearwardly from said point.

15. A coke plant machine having a longitudinally movable ram, a coal leveler head on said ram and terminating in a point at the front bottom end thereof and in a point at
30 the rear bottom end thereof, and walls slop-
ing upwardly and rearwardly from said point at the front and upwardly and forwardly from said point at rear.

In testimony of the foregoing I affix my
35 signature.

EUGENE W. SCHELLENTRAGER.
